UNITED STATES PATENT OFFICE.

CHARLES JULIUS KLEIN, OF NEW YORK, N. Y., ASSIGNOR TO THE GENERAL INCANDESCENT ARC LIGHT COMPANY, OF SAME PLACE.

PANEL-BOARD AND FUSE-HOLDER.

SPECIFICATION forming part of Letters Patent No. 660,113, dated October 23, 1900.

Application filed March 14, 1900. Serial No. 8,602. (No model.)

To all whom it may concern:

Be it known that I, CHARLES JULIUS KLEIN, a citizen of the United States, residing in the city, county, and State of New York, have invented certain new and useful Improvements in Panel-Boards and Fuse-Holders, of which the following is a specification.

My invention relates to panel-boards and fuse-holders adapted for use therewith.

10 In the accompanying drawings I have shown a panel-board and fuse-holders which illustrate my invention, it being understood that the details may be varied without departing from the spirit of my invention, which is concisely defined in the claims.

15 In the drawings, Figure 1 is a plan view of a panel-board constructed in accordance with my invention. Fig. 2 is a sectional view thereof, showing a sliding fuse-holder in place, the 20 section being taken on line 2 2 of Fig. 1. Fig. 3 is a sectional view of the panel-board on line 3 3 of Fig. 2, the fuse-holder being shown in end elevation. Fig. 4 is a plan view of the fuse-holder. Fig. 5 is a plan view of the fuse- 25 holder with the cover removed to show the interior arrangement. Fig. 6 is a section on line 6 6 of Fig. 5. Fig. 7 shows a side elevation of a means for imparting a "snap" movement to the sliding fuse-holder, and Fig. 8 30 shows a swinging fuse-holder.

The main objects of my invention, briefly stated, are these:

First, to decrease the width or size of the panel-board and at the same time separate 35 the opposite terminals of the branch circuits as far as possible. This I do by mounting the bus-bars edgewise and in two-wire systems mounting the like terminals of the branch circuits upon the same side of the bus-bars.

40 Second, to improve the construction of the removable fuse-holders and to bridge all the bus-bars and effect direct connections from the working bus-bars to the branch-circuit terminals.

45 In the drawings, 1 represents the slate base of the panel-board, and 2 3 4 the bus-bars. These bus-bars are suitably secured to the base, preferably, by bolts 5. These bus-bars are set up edgewise to the slate base and may 50 be provided with suitable binding-sockets 6.

The panel-board may be built either for the three-wire, two-wire, or other system of lighting. In cases where it is desirable one or more of the bus-bars may be reinforced by an additional strip or bar 8, which, however, is preferably spaced away from the bar which it reinforces. These bus-bars are available for connection with the terminals 9 and 10 of the branch circuits by simple connections, as will be described, and the employment of baby 55 knife-switches is thus avoided. All the terminals 10 on one side of the board may be of one polarity, and similarly all the terminals 9 are of the opposite polarity. By this means the distance between unlike terminals of the 60 same branch circuit is increased as far as possible without adding to the necessary size of the panel-board. The circuit connections are preferably made by a movable or removable fuse carrier or holder, of which two forms 65 are shown in the drawings, although this idea is capable of great variation without departing from the spirit of my invention.

In Figs. 2 to 6, inclusive, I have shown a 70 form of sliding fuse-carrier which bridges all the bus-bars and carries the fuses. The rigid body 11 or block of the fuse-holder or fuse-carrier is suitably recessed to receive fuses, connections, &c., and in the use of the terms "fuse-holder" or "fuse-carrier" equivalent means for carrying clips and completing a circuit are also to be understood, as my invention is not limited to the use of fuse-carriers. The vertical apertures 12 receive the guiding-bolts 13, which are fixed in the 75 slate base and serve to guide the fuse-carrier in its up and down movements, which are imparted to it by a suitable porcelain handle 14, carried upon a screw 15^a, which is socketed in the block 11. The fuses 15 are carried in recesses 16 of the general shape of the letter I—that is, they consist of two enlarged recesses in which binding-terminals 17 are seated, united by a narrow passage in which the fuse 15 is located. These recesses 95 are covered in use by suitable insulating-plates 18 and the whole covered by a cover 19, having spaces 20 for a directory, which is required by the fire laws of some cities. This cover is provided with lugs 21, which en- 100

gage the block 11, and is held in place by the knob or handle 14. The binding-terminals 17 extend through the block 11 and are provided with "clips" 22, by which term I mean 5 to include any and every means for removably engaging the "edge-on" bus-bars and making efficient electrical contact therewith. Two variations of this idea are shown in Fig. 2, wherein the clips 22, engaging the bus-bars 10 2 and 4, embrace the same, whereas the clips 22 embrace the bar 3 and one of them is wedged in between the bars 3 and 8. In the form of the structure shown the block 11 is represented as provided with clips 22, carried 15 upon a terminal binding-screw 23, which is connected to the fuse by a wire 24, lying in a suitable recess 25 in the block. This construction is necessitated by reason of the fact that the panel-board is used in a three-wire 20 system. If the two-wire system were used, the clips could be attached directly to all the binding-terminals of the fuses, as shown in dotted lines in Fig. 6. It will be understood 25 that the clips may be disengaged from the bus-bars by lifting the block on its rods 13 by means of the knob. In service the clips engage the bus-bars with sufficient force to retain the block in place. Of course I do not limit myself to employing a sliding fuse- 30 holder, but may use other forms. For instance, in Fig. 8 I have shown a fuse-holder hinged to standards 26, of which only one is shown. Suitable means may likewise be provided to insure a snap action in either form 35 of fuse-holder. For instance, in Fig. 7 I have shown the fuse-holder as provided with a rounded portion resting between springs 27, mounted on the base 1. Other forms of snap action may be used.

40 Having described my invention, what I claim as new, and desire to secure by Letters Patent, is—

1. In a panel-board, the combination of bus-bars having edgewise - mounted portions 45 adapted to be engaged by a clip and a device for bridging and connecting the bus-bars in circuit consisting of a body carrying clips adapted for engagement with the edges presented by the bus-bars.

50 2. In a panel-board, the combination of an insulating-base, bus-bars mounted edgewise thereon, and a movable circuit-connector consisting of a body provided with clips adapted to removably engage the edges of the said bus-bars to make electrical connection therewith.

55 3. In a panel-board, the combination of bus-bars comprising metallic strips mounted edgewise on the panel-board and circuit-terminals 60 likewise mounted upon the said panel-board on opposite sides of the group of bus-bars, and a circuit-connector having clips adapted for engagement with the bus-bars, bridging the said bus-bars and connecting the same to 65 the appropriate branch-circuit terminals on opposite sides thereof.

4. In a panel-board, the combination of an

insulating-base, bus-bars mounted edgewise thereon, one of the said bars having a reinforcing-strip 8 also mounted edgewise and in electrical connection with the said bus-bar and a movable circuit connector-provided with clips adapted for engagement with the bus-bars. 70

5. In a panel-board, the combination of an insulating - base, a plurality of bus - bars mounted edgewise thereon and a movable fuse-carrier provided with clips adapted for engagement with the bus-bars. 75

6. In a panel-board, the combination of an insulating - base, a plurality of bus - bars 80 mounted edgewise thereon, a movable fuse-carrier provided with clips adapted for engagement with the bus-bars, and branch-circuit terminals likewise mounted upon the insulating-base and adapted for connection with 85 the fuse-carrier.

7. The combination of a suitable panel-board provided with bus-bars mounted edgewise thereon, a movable fuse-carrier provided with clips adapted to engage the said bus-bars 90 and means for imparting a snap switch action to the said movable fuse-carrier.

8. In a fuse-carrier, the combination of a block provided with fuses and clips electrically connected to the said fuses carried by the 95 said fuse-block and adapted for engagement with edgewise-mounted bus-bars.

9. In a fuse-carrier, the combination of a recessed fuse-block and a removable cover therefor provided with panels for a directory 100 and clips adapted to engage edgewise-mounted bus-bars.

10. In a panel-board structure, the combination of bus-bars consisting of metallic strips mounted edgewise, a branch-circuit terminal 105 on each side of the said group of bus-bars and a movable fuse-carrier provided with clips adapted to engage the bus - bars and the branch-circuit terminals and to bridge all the bus-bars. 110

11. In a panel-board structure, the combination of a group of bus-bars, branch-circuit terminals in proximity to the said group of bus-bars and a circuit-connector bridging all of the bus-bars and provided with clips adapted 115 to make electrical connection with two or more of the bus-bars and the branch-circuit terminals.

12. The combination of a panel-board, a group of bus-bars mounted thereon and comprising in their structure circuit-terminals adapted for engagement by a clip, branch-circuit terminals on each side of the group of bus-bars and also adapted for engagement by a clip and a rigid body extending across the 125 bus-bars and provided with clips and conductors adapted to bridge the bus-bars and complete the circuit between two or more of the bus-bars and the branch-circuit terminals.

13. The combination of a base, a group of 130 metallic strips mounted edgewise on said base, a branch-circuit terminal, on each side of the group of strips, and a movable fuse-carrier, provided with clips adapted to engage with

the strips and circuit-terminals; the said fuse-carrier bridging all the strips.

14. In combination a base carrying edge-wise-mounted strips, and a bodily-sliding fuse-carrier having clips adapted to engage the edges of the strips.

15. In combination, a base carrying edge-wise-set strips, a bodily-sliding fuse-carrier having clips to engage the strips and a guide 10 for guiding the fuse-carrier.

16. In combination, a base carrying edge-wise-set strips, and a fuse-carrier having clips embracing the edges of the said strips.

17. In combination, a base carrying edge-wise-set strips, and a sliding fuse-carrier having 15 clips embracing the said strips.

18. A panel-board comprising a base, two or more bus-bars, a series of circuit-terminals on opposite sides of said group of bus-bars 20 and means for simultaneously bridging said bus-bars and circuit-terminals.

19. A panel-board comprising a base, two or more bus-bars, a series of circuit-terminals on opposite sides of said group of bus-bars 25 and means for simultaneously bridging said

bus-bars and circuit-terminals through fusible conductors.

20. A panel-board comprising a base, two or more longitudinally-arranged bus-bars, a series of circuit-terminals on opposite sides of 30 said group of bus-bars and means for simultaneously bridging said bus-bars and circuit-terminals, comprising a holder carrying a number of resilient contacts corresponding in number and position with the bus-bars and 35 contact-terminals.

21. A panel-board comprising a base, two or more longitudinally-arranged bus-bars, a series of circuit-terminals on opposite sides of 40 said group of bus-bars and means for simultaneously bridging the said bus-bars and circuit-terminals comprising a holder carrying a number of resilient contacts corresponding in number and position with the bus-bars and 45 contact-terminals, and such contacts suitably connected through fusible conductors.

CHARLES JULIUS KLEIN.
